FOUNTAIN PEN CAP AND SECTION

Solomon M. Sager, Glencoe, Ill.

Application February 25, 1931, Serial No. 518,072

1 Claim. (Cl. 120—42)

In the use of various makes of fountain pens, it has been found that when the fountain pen is not in use and the writing end thereof is enclosed by the ordinary fountain pen cap that 5 excess ink remaining in the feeder and on the pen point accumulates around the outer end of the fountain pen section, with the result that the excess ink leaks off of the end of the section and collects in the fountain pen cap. Due to the leakage of ink from the fountain pen into the fountain pen cap, the interior of the cap and exterior of the fountain pen section become stained with the excess ink so that when the fountain pen is again used the hands of a user become stained 10 with the excess ink.

For the purpose of obviating the leakage of ink from the feed bar and pen point to the exterior of the fountain pen section and the interior of the fountain pen cap, this invention has been devised for the purpose of providing a fountain pen with a beveled section adapted to tightly interfit with a beveled liner or sleeve engaged in the closed end of the fountain pen cap to produce a non-leakable joint or fit between the section 20 and the cap liner to produce an air tight chamber enclosing the feed bar and pen point so that any excess ink remaining on the pen point or in the outer end of the feed bar is prevented from leaking into the cap but is allowed to accumulate in 25 a receiving pocket provided in an ink guard member forming the outer end of the fountain pen section and affording an arrangement whereby the accumulated excess ink is permitted to gradually flow back through the feed bar grooves into 30 the ink chamber of the fountain pen barrel.

It is an object of this invention to provide a fountain pen with a section having a beveled ink guard formed thereon to interfit with the beveled end of a cap liner sleeve to completely obviate 40 the leakage of ink from the fountain pen feed bar and pen point into the portion of the cap which surrounds the section and the section carrying end of the fountain pen barrel.

It is also an object of this invention to provide 45 a fountain pen wherein the fountain pen section and the cap liner sleeve are both provided with beveled surfaces adapted to be brought into tight interfitting relation when the cap is engaged in place to obviate leakage of ink into the fountain pen cap and around the exterior of the fountain pen section.

A further object of the invention is to provide 50 a fountain pen with a section having a chambered beveled ink guard positioned to the exterior of the peripheral flange of the section to permit the

beveled end surface of an inner cap secured in the closed end of the fountain pen cap to be brought into tight frictional contact with the beveled surface of the section ink guard to obviate the leakage of ink from the interior of the inner cap and, 60 from the writing end of the fountain pen into the outer or main cap of the fountain pen.

It is furthermore an object of this invention to provide a fountain pen having a closure cap provided with an interior cap closed at one end 65 and having a beveled surface at the opposite end to form a tight frictional fit with the beveled end surface of the fountain pen section to form a tight chamber between the section and the inner cap and around the pen point and feed bar to 70 prevent the leakage of excess ink into the chamber surrounding the fountain pen section when the main closure cap is engaged on the fountain pen barrel.

An important object of the invention is the 75 provision of an improved fountain pen wherein a beveled surface of a fountain pen section and the beveled surface of an inner cap or sleeve provided in the main fountain pen cap are adapted to be brought into rotational frictional engagement, 80 obviating the squeezing or forcing of any excess ink outwardly into the main cap, but allowing the excess ink between the bevel surfaces to flow inwardly into a pocket or groove in the section.

Other and further important objects of this 85 invention will be apparent from the disclosures in the specification and the accompanying drawing.

The invention (in a preferred form) is illustrated in the drawing and hereinafter more fully described.

On the drawing:

Figure 1 is an enlarged fragmentary sectional view of the pen point end of a fountain pen equipped with an improved section and an improved inner cap embodying the principles of this 95 invention and showing the section and inner cap with the beveled surfaces thereof tightly interlocked.

Figure 2 is a reduced longitudinal section of the fountain pen cap illustrating the improved inner 100 cap in elevation.

Figure 3 is a fragmentary elevational view of the fountain pen section illustrating the beveled end surface and the excess ink-receiving chamber provided in the ink guard member or end of 105 the section.

As shown on the drawing:

The reference numeral 1 indicates a fountain pen barrel provided with an ink chamber 2 and having the open end thereof internally threaded 110

at 3 and externally threaded at 4. Threaded into the internally threaded portion 3 of the barrel is the externally threaded shank 7 of an improved fountain pen section embodying improved features of this invention. The threaded shank 7 is integrally formed on the inner end of an externally tapered section body 8 the interior of which is provided with an axial passage 9, the inner end of which terminates in the chamber 10 of the shank portion 7 while the opposite end communicates with the inner end of a surplus or excess ink receiving pocket or recess 5 provided in an extension sleeve or collar 6 which serves as an ink guard member and which is integrally formed on the outer end of the body of the section 8 to the outside of a stop ring or flange 11. The flange 11 is integrally formed externally on the outer end portion of the section body 8 where it joins the ink guard sleeve or collar 6. The ink guard sleeve or collar 6 has the end thereof reamed out or formed to provide an inner beveled end surface 12. The beveled surface 12 extends inwardly and joins the walls forming the excess ink chamber 5 of the ink guard member.

Engaged in the section 8 and projecting through the ink guard member 6 is an ink feed bar 13 and a pen point 14 with the walls of the excess ink chamber 6 spaced from and surrounding the feed bar and pen point to permit excess ink from the feed bar and pen point to flow back into the chamber 5 to permit the excess ink to eventually flow back into the ink chamber 2 of the fountain pen barrel when the fountain pen is positioned in an upright position with the pen point pointing upwardly.

The fountain pen is provided with a main or outer cap 15 open at one end and closed at the opposite end 16. The interior of the main cap 15 is provided with an interiorly threaded section 17 adapted to be threaded on the exteriorly threaded portion 4 of the ink barrel 1 when the outer cap is positioned as illustrated in Figure 1 to enclose the writing end of the fountain pen.

Tightly wedged or otherwise rigidly secured within the closed end 16 of the main outer cap 15 is an improved inner cap or liner embodying another of the improved members of the fountain pen. The inner cap or liner comprises an enlarged sleeve or body portion 18 one end of which is shaped or formed to provide an exterior beveled end surface 19 adapted to be moved into tight frictional interfitting contact with the beveled surface 12 of the ink guard member 6 when the outer fountain pen cap is engaged on the barrel 1 to enclose the writing end of the fountain pen. Integrally formed on the opposite end of the inner cap sleeve or body portion 18 is a closed end section or head portion 20 of reduced diameter to tightly fit within a complementally shaped chamber provided in the closed end 16 of the outer cap 15, as clearly illustrated in Figure 1. The inner fountain pen cap has the exterior surfaces thereof tightly contacting the inner surfaces of the closed end of the cap 16 with the exception of the beveled end surface 19 which is spaced from the interior surface of the cap 15 to permit the inner cap beveled surface 19 to be rotatably advanced into frictional interfitting engagement with the beveled end surface 12 of the ink guard member 6 when the outer cap 15 is threaded over the exteriorly threaded portion 4 of the fountain pen barrel 1, as clearly illustrated in Figure 1.

When the outer fountain pen cap is engaged on

the fountain pen barrel as illustrated in Figure 1, the beveled end of the inner cap is adapted to telescope into or interfit with the beveled outer end of the ink guard collar or member 6 of the fountain pen section to provide an air tight chamber 21 between the interfitting section and inner cap so that any excess ink remaining on the pen point 14 or on the feed bar 13 is prevented from leaking out of the chamber 21 into the chamber 22 which surrounds the outer portion of the section 8 and the ink guard 6 forming a part thereof. It will thus be noted that the improved beveled inner cap rotationally interfitting with the beveled end of the section affords a self-cleaning arrangement of the beveled surfaces and obviates any tendency of excess ink returned from the pen point and the feed bar to leak or be squeezed outwardly between the interfitting beveled surfaces out of the chamber 21 into the chamber 22 provided in the outer cap 15. The interior surfaces of the outer cap 15 and the exterior surfaces of the ink guard 6 and the section 8 are thus kept clean of ink accumulation which, in earlier types of fountain pens, has been one of the defects which have always caused considerable trouble and annoyance to users of fountain pens. With the improved beveled inner cap and ink guard member 6 tightly interfitting one another when the outer cap 15 is engaged on the fountain pen barrel 1 the excess ink on the pen point 14 and in the feed bar 13 is forced or pushed inwardly by the beveled end of the inner cap into the receiving chamber 5 of the ink guard 6, allowing the ink to be gradually returned into the chamber 2 of the fountain pen barrel.

When the fountain pen is not in use, the outer cap 15 is adapted to be threaded onto the fountain pen barrel 1 an amount sufficient to permit the beveled end of the inner cap 18 to be projected into the end of the ink guard 6 with the inner cap beveled surface 19 and the beveled surface 12 of the ink guard 6 frictionally interfitting one another to form a tight fit between the fountain pen section and the inner cap so that regardless of the position of the fountain pen when the same is closed, the leakage of ink from the chamber 21 between the ink guard 6 and the inner cap 18 into the chamber 22 of the outer cap 15 is completely eliminated.

It will, of course, be understood that various details of construction may be varied through a wide range without departing from the principles of this invention, and it is therefore not the purpose to limit the patent granted hereon otherwise than is necessitated by the scope of the appended claim.

I claim as my invention:

In a fountain pen, the combination with a pen barrel, of a section secured therein having an external flange formed thereon and having a portion of increased bore extending outwardly beyond said flange to define a space for the reception of ink leaking from the pen, the outer end of said section having an inner beveled end surface, and a cap for said pen removably threaded on said barrel to enclose said section, said cap being provided with an inner cap firmly secured therein, said inner cap having a beveled end to telescope within the outer end of said section and make a wiping contact with the beveled end surface thereof as the outer cap is screwed in position.

SOLOMON M. SAGER.
